ATTORNEY

UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

RADIODETECTOR.

Application filed October 15, 1923. Serial No. 668,554.

My invention relates to a transmission of intelligence by electrical means.

Broadly speaking, the object of my invention is to provide a more convenient form of detector for radio frequency signals.

Specifically, the object of my invention is to provide a detector which shall be more convenient to use and more readily kept in adjustment than the detectors of the prior art.

In the prior art of the detection of radio signals, a number of substances have been found to have such properties of unilateral conductivity as to be sensitive to radio signals. In some of these substances, this property is manifested only upon certain areas of the surface of the substance, while with others, the sensitivity is more uniformly distributed over the material, but is not high.

I have found that a mixture made up of powdered carborundum, amorphous carbon and a bonding agent such as kaolin or water-glass has the property of changing its effective resistance with a change in applied voltage, that is, its conductivity is non-rectilinear.

I find that by preparing such a mixture, inserting it in series with a signal indicator and a source of biasing potential, it becomes sensitive to radio frequency currents. This property makes it suitable for the detection of radio signals.

Other objects and structural details of my invention will be apparent from the following description and claims, when read in connection with the accompanying drawings, wherein:

Figure 1 is a diagrammatic view of a radio receiving system embodying my invention.

Fig. 2 is a curve of the apparent change in resistance, with change in applied voltage, of the material forming the detector of my device, and

Fig. 3 is a curve showing the change in current flow with change of voltage applied to the material forming the detector of my device.

In Fig. 1 is shown a receiving system comprising an aerial 1, a tuning inductance 2, a ground 3, a signal receiver 4, a battery 5, a shunting condenser 6, a detector 7, connector wires 8 and 9 and a potentiometer 10.

The detector 7 consists of conducting plates 11 and 12 on opposite sides of a mass

14 of the previously mentioned composition of carborundum, amorphous carbon and bonding agent.

Fig. 2 shows the curve of the change in resistance, with change in applied voltage, of the composition of which my detector is made. As shown in the curve, the material shows a maximum resistance when measured with a very low applied voltage. As the applied voltage is raised, the resistance becomes less.

Fig. 3 shows the relation between the applied voltage and the current flow. It will be noticed that a small voltage will produce a given current and that an increase in voltage produces more than a proportional increase in current over a range of a few applied volts.

In operation, the potential battery 5 is adjusted, by means of the potentiometer 10, until the voltage drop across the mass 14 of detector 7 is such as to bring the current value to the bend of the curve of Fig. 3, indicated by point *a*. The circuit comprising aerial 1, tuning inductance 2 and ground 3 is then brought into resonance with the incoming signals. Upon the arrival of signals, high frequency is impressed across the terminals of detector 7 by way of connecting leads 8 and 9 and shunting condenser 6. The potential of battery 5 having been adjusted to provide an applied potential across detector 7 corresponding to point *a* of Fig. 3, and a current through its detector corresponding to point *b*, an incoming high frequency signal will produce a change in current through the signal indicator 4 and battery 5 by virtue of the non-rectilinear conductivity of the detector in the following manner.

If the first half cycle of the high frequency current happens to have a polarity which is additive with the applied voltage of the polarizing battery, raising the voltage to point *c*, the increased voltage brings into effect the reduction of resistance with increased voltage, and a current larger than is proportionate to the previous voltage and current will flow from battery 5 through phones 4, detector 7 and the circuit, as shown by point *d*. The next half cycle of the high-frequency current will be in opposition to the battery voltage and therefore subtractive, producing a voltage corresponding to point *e*. The lower voltage will bring into

play the effectively higher resistance of the detector 7. Since the effective resistance of the material is higher, a reduction in current from battery 5 through signal indicator 4 to point f will occur, which reduction will, however, be proportionately less in value than the increase in current produced by the preceding half cycle. In this way, the presence of a high-frequency current in the circuit influences the average current flowing from battery 5, causing an increase in its value equal to the difference between the increase produced by one half wave over the decrease produced by the other half wave of the received signal, which occurs during the period of the reception of the signal. The increase of current during the time of the signal produces an effect on the signal indicator 4, thereby rendering the signal perceptible.

In this way my device, in operation, gives rectification and detection of incoming radio frequency signals.

While I have shown only one embodiment of my invention in the accompanying drawings, it is capable of various changes and modifications without departing from the spirit thereof and it is desired, therefore, that only such limitations shall be imposed thereon as are indicated in the prior art or in the appended claims.

I claim as my invention:

1. A radio detector comprising a body having a non-rectilinear conductivity, said body comprising a mixture of carborundum, amorphous carbon and a binder.

2. A radio detector comprising a body having a non-rectilinear conductivity, said body comprising a mixture of powdered carborundum, lampblack and a bonding agent, said bonding agent comprising sodium silicate.

In testimony whereof, I have hereunto subscribed my name this 9th day of October, 1923.

JOSEPH SLEPIAN.
